HANDLE FOR A WAX PAPER MILK CONTAINER OR SIMILAR ARTICLE

Albert V. Olson, Santa Monica, Calif.

Application November 1, 1948, Serial No. 149,418

Term of patent 7 years

(Cl. D58—26)

To all whom it may concern:

Be it known that I, Albert V. Olson, a citizen of the United States, residing at Santa Monica, in the county of Los Angeles and State of California, have invented a new, original, and ornamental Design for a Handle for a Wax Paper Milk Container or Similar Article, of which the following is a specification, reference being had to the accompanying drawing, forming a part thereof.

Figure 1 is a perspective view of a handle for a wax paper milk container, showing my new design. The milk container shown in broken lines is for illustrative purposes only.

Figure 2 is a top plan view of the handle of Figure 1.

Figure 3 is a transverse vertical sectional view taken on the line 3—3 of Figure 1.

Figure 4 is a transverse vertical sectional view taken upon the line 4—4 of Figure 1.

Figure 5 is a horizontal sectional view, taken upon the line 5—5 of Figure 1.

I claim:

The ornamental design for a handle for a wax paper milk container or similar article, substantially as shown and described.

ALBERT V. OLSON.
